UNITED STATES PATENT OFFICE.

ENOCH P. STEVENS, OF CHICAGO, ILLINOIS.

PALLET FOR DRYING BRICKS.

1,150,074.

Specification of Letters Patent. Patented Aug. 17, 1915.

Application filed August 31, 1914. Serial No. 859,305.

To all whom it may concern:

Be it known that I, ENOCH P. STEVENS, a citizen of the United States, residing at Chicago, in the county of Cook and State of Illinois, have invented certain new and useful Improvements in Pallets for Drying Bricks, of which the following is a specification.

My invention relates to an improved pallet construction for use particularly in connection with the drying of bricks.

In the past it has been customary to make these devices of wood, and, in some cases, of sheet metal, but in the latter case the construction has heretofore necessarily involved building up the structure from separate pieces of metal and securing the parts together with rivets or equivalent fastening devices. As is well known in the art, it is necessary to use in any brick-making plant a large number of these devices, and wooden pallets have been unsatisfactory on account of their lack of durability and relative cost, while the metal pallets heretofore used have been unsatisfactory owing to the large expense involved in constructing the same, making their use prohibitive in many cases.

It is the object of my present invention to construct a pallet of sheet metal in such a manner that the cost of manufacturing is reduced to a small amount as compared with the cost of the material itself, as a result of which my metal pallets are inexpensive to construct, and at the same time the resulting structure is more substantial and rigid than has been the case with metal pallets heretofore produced.

These advantages I secure by cutting a blank of sheet metal so that it may be folded up to form reinforcing flanges and supporting legs for the main supporting surface of the pallet, and at the same time forming an interlocking construction for securing the legs in their supporting position so that they are rigidly and permanently held in place.

By my construction I also provide an improved handle arrangement for lifting the pallets by turning in a portion of each end of the blank, in a manner to be described.

My pallet construction is applicable to any desired form of pallet, as the supporting surface may be made either flat or curved, as desired, and thus the bricks that are to be dried on these pallets will have a rigid smooth support which will positively pro-

teet them from injury or deformation during the drying operation.

The several drawings illustrating my invention are as follows:

Figure 1 shows in developed view a blank as laid out and cut for forming a pallet having a curved supporting surface; Fig. 2 shows in a view similar to Fig. 1 a modified form of blank for forming a pallet having a flat supporting surface; Fig. 3 shows in perspective view a pallet formed from one of the blanks shown in Fig. 1; Fig. 4 is a vertical sectional view through the pallet shown in Fig. 3 taken along the line 4—4; Fig. 5 is a bottom view of a completely formed pallet which is substantially the same for either form of pallet; Fig. 6 shows in a view similar to Fig. 4 a pallet formed from a blank similar to that shown in Fig. 2; and Fig. 7 is a vertical sectional view through the pallet shown in Fig. 3 taken along the line 7—7.

Similar numerals refer to similar parts throughout the several figures.

As shown in Fig. 1, the blank consists of a main supporting surface 10 bounded by two longitudinal lines of fold 11 and 12 and two transverse lines of fold 13 and 14.

The portions 15 and 16 constitute, when the blank is folded up, flanges on opposite sides of the main supporting surface 10 for stiffening and reinforcing the same, and the ends of these flanges are formed by cuts 17, 17 for the flange 15 and 18, 18 for the flange 16 at such an angle that the inclined portions of the flanges 19, 20, 21 and 22 formed on the ends of the leg sections 23 and 24, respectively, when bent at substantially right angles to the planes of these leg sections will rest against the under surface of the main supporting portion 10 of the pallet.

The leg sections 23 and 24 are bent along the lines 13 and 14 so as to occupy a substantially vertical position, and when in this position, with their end flanges 19, 20, 21 and 22 bent at substantially right angles to the planes of the leg sections, the pointed ends of the downwardly-extending flanges 15 and 16 are bent around the outside of the leg sections, as indicated in Fig. 3. As a result, the leg sections are firmly held against motion in either direction, motion in one direction being prevented by the engagement of the beveled ends of the flanges 19, 20, 21 and 22 with the under surface of the main supporting portion 10 of the pallet,

and motion in the other direction being prevented by the turned-in ends of the flanges 15 and 16. Thus a rigid and permanent leg structure is provided without the use of any auxiliary or additional fastening devices.

Each of the leg sections 23 and 24 is provided with two inwardly-extending cuts 25 and 26 so that the portion 28 of the blank between them may be folded inwardly about 10 the line of the fold 27, as indicated more clearly in Fig. 4, so that the portion 28 constitutes a hand-hold for lifting the pallet and the brick or bricks that may rest thereon. It is desirable that the portion 28 shall 15 not be turned inward at a sharp angle, since a well rounded corner at the line of fold is more satisfactory for engagement by the hand than is a sharply turned corner. The inner ends of the cuts 25 and 26 are prefer- 20 ably extended toward the flanges 19 and 20 a short distance, as indicated at 29 and 30, so that the edges of the leg portion adjacent to the hand-hold may be turned inward to form reinforcing flanges 31, as indicated in 25 Figs. 3 and 5. As a result of this construction, the legs of the pallet are made perfectly rigid so that they cannot be deformed by any treatment the pallet is apt to receive.

30 In forming the pallet the main supporting portion of the blank is preferably clamped between dies having the desired surface of curvature for the form shown in Fig. 1, or flat for the form shown in Fig. 2, these dies 35 being of a size corresponding with the lines of fold 11, 12, 13 and 14. When clamped in this position the leg sections 23 and 24 are first folded around against the side faces of one of the die members either by forming- 40 dies or by hammering the blank into the required position, and then the flanges 19, 20, 21 and 22 are folded over onto the top and bottom surfaces of the same die member either by forming-dies or by hammering. 45 Then the flanges 15 and 16 are folded over against the top and bottom surfaces of the same die member either by forming-dies or by hammering, and the pointed end portions of the flanges 15 and 16 are folded 50 around against the outside surfaces of the leg sections 23 and 24 either by forming-dies or hammering. The pallet thus far completed is then removed from the dies and the hand-holds are made by bending in the 55 sections 28 either by forming-dies or hammering, and the flanges 31 are also bent inward either by forming-dies or hammering to the position indicated in Figs. 3 and 5. The resultant pallet, in addition to being 60 very cheap to make, since the operations may be rapidly and easily performed, is particularly adapted for the purpose for which it is intended, as the main supporting surface is smooth throughout its entire extent and 65 entirely free from rivets or other fastening

devices, and thus affords an ideal surface for supporting the bricks during the drying of the same.

For bricks of curved conformation the form of pallet shown in Fig. 3 is employed, 70 while for bricks having flat surfaces the form of pallet shown in Fig. 6 is employed. For bricks having curved surfaces the main supporting surface 10 of the pallet is, of course, given a degree of curvature con- 75 formed exactly to the curved surface of the bricks, so that the bricks may be properly supported throughout during the drying of the same.

The blank shown in Fig. 2 is similar 80 to the blank shown in Fig. 1, with the exception of the cuts 17^a and 18^a. Since this blank is designed for a pallet having a flat main supporting surface, the cuts are extended for a portion of the distance across the flanges 85 15^a and 16^a in line with the lines of folds 13^a and 14^a, from which point these cuts are continued in substantially the same general direction as the cuts 17 and 18. As a result of this construction, when the blank is folded 90 into position in substantially the same manner as described above for the blank shown in Fig. 1 the portions of the upper ends of the flanges 19^a, 20^a, 21^a, and 22^a, which are squared with the adjacent lines of fold, rest 95 against the under surface of the main supporting portion of the pallet, while the remaining portions of these cuts provide the required extensions of the ends of the flanges 15^a and 16^a to fold around against the outer 100 surfaces of the leg sections to rigidly secure them in position substantially at right angles to the main supporting surface of the pallet.

It will be understood that my improved construction is applicable to a wide range 105 of sizes and proportions, and that I do not limit myself to the exact arrangement shown, for the detail of the interlocking supports for the leg sections and the detail construction of the hand-holds may be modified to 110 meet various requirements without departing from the spirit of my invention.

What I claim is:

1. A pallet for drying bricks, consisting of a single sheet of metal comprising a main 115 supporting portion, leg sections extending at an angle from said main supporting portion, flanges extending from said main supporting portion in substantially the same direction as the leg sections, and projections 120 extending from the leg sections and said flanges to rigidly hold said leg sections in supporting position.

2. A pallet for drying bricks, consisting of a single sheet of metal comprising a main 125 supporting portion, leg sections extending at an angle from said main supporting portion, flanges extending from said main supporting portion in substantially the same direction as the leg sections, and projections 130

extending from the leg sections and said flanges to rigidly hold said leg sections in supporting position, said leg sections having bent portions constituting hand-holds.

5. 3. A pallet for supporting bricks during the drying of the same, consisting of a single sheet of metal formed to constitute a main supporting portion, leg sections extending at an angle from said main supporting portion to support the same, and flanges extending from the edges of said main supporting portion and having projections folded around said leg sections to reinforce said leg sections and hold them in supporting position.

10. 4. A pallet for supporting bricks during the drying of the same, consisting of a single sheet of metal formed to constitute a main supporting portion, leg sections extending at an angle from said main supporting portion to support the same, and flanges extending from the edges of said main supporting portion and having projections folded around said leg sections to reinforce said leg sections and hold them in supporting position, portions of said leg sections being bent therefrom to form hand-holds for carrying the pallet.

15. 5. A pallet for supporting bricks during the drying of the same, consisting of a single sheet of metal having a main supporting portion, flanges extending at substantially right angles from said main supporting portion along opposite sides thereof, and leg sections extending in substantially parallel arrangement at an angle to said main supporting portion in substantially the same direction as said flanges, said leg sections having flanges formed on their outer edges 20 to engage the under surface of said main supporting portion and the flanges formed on the opposite sides of said main supporting portion having projections folded into engagement with the outer surfaces of said leg sections to hold said leg flanges in said engagement.

25. 6. A pallet for supporting bricks during the drying of the same, consisting of a single sheet of metal having a main supporting portion, flanges extending at substantially right angles from said main supporting portion along opposite sides thereof, and leg sections extending in substantially parallel arrangement at an angle to said main supporting portion in substantially the same direction as said flanges, said leg sections having flanges formed on their outer edges 30 to engage the under surface of said main supporting portion and the flanges formed on the opposite sides of said main supporting portion having projections folded into engagement with the outer surfaces of said leg sections to hold said leg flanges in said engagement, said leg sections having in-turned portions forming hand-holds and

provided also with in-turned flanges adjacent to said hand-holds.

7. A pallet for supporting bricks during the drying of the same, consisting of a single sheet of metal formed to constitute a main supporting portion having a curved supporting surface, leg sections extending at an angle from said main supporting portion to support the same, and flanges extending from the edges of said main supporting portion and having projections folded around said leg sections to reinforce said leg sections and hold them in supporting position.

8. A pallet for supporting bricks during the drying of the same, consisting of a single sheet of metal formed to constitute a main supporting portion having a curved supporting surface, leg sections extending at an angle from said main supporting portion to support the same, and flanges extending from the edges of said main supporting portion and having projections folded around said leg sections to reinforce said leg sections and hold them in supporting position, portions of said leg sections being bent therefrom to form hand-holds for carrying the pallet.

9. A pallet for supporting bricks during the drying of the same, consisting of a single sheet of metal having a main supporting portion with a curved supporting surface, flanges extending at substantially right angles from said main supporting portion along opposite sides thereof, and leg sections extending in substantially parallel arrangement at an angle to said main supporting portion in substantially the same direction as said flanges, said leg sections having flanges formed on their outer edges 35 to engage the under surface of said main supporting portion and the flanges formed on the opposite sides of said main supporting portion having projections folded into engagement with the outer surfaces of said leg sections to hold said leg flanges in said engagement.

10. A pallet for supporting bricks during the drying of the same, consisting of a single sheet of metal having a main supporting portion with a curved supporting surface, flanges extending at substantially right angles from said main supporting portion along opposite sides thereof, and leg sections extending in substantially parallel arrangement at an angle to said main supporting portion in substantially the same direction as said flanges, said leg sections having flanges formed on their outer edges 40 to engage the under surface of said main supporting portion and the flanges formed on the opposite sides of said main supporting portion having projections folded into engagement with the outer surfaces of said leg sections to hold said leg flanges in said engagement.

11. A pallet for supporting bricks during the drying of the same, consisting of a single sheet of metal having a main supporting portion with a curved supporting surface, flanges extending at substantially right angles from said main supporting portion along opposite sides thereof, and leg sections extending in substantially parallel arrangement at an angle to said main supporting portion in substantially the same direction as said flanges, said leg sections having flanges formed on their outer edges 45 to engage the under surface of said main supporting portion and the flanges formed on the opposite sides of said main supporting portion having projections folded into engagement with the outer surfaces of said leg sections to hold said leg flanges in said engagement, said leg sections having in-turned portions forming hand-holds and

portions forming hand-holds and provided also with in-turned flanges adjacent to said hand-holds.

11. A pallet for supporting bricks during the drying of the same, consisting of a main supporting portion of sheet metal, leg sections extending at an angle from said main supporting portion, and flanges extending from said main supporting portion, said flanges serving to reinforce said leg sections.

12. A pallet for supporting bricks during the drying of the same, consisting of a sheet of metal having a main supporting portion,

leg sections extending at an angle from said main supporting portion to support the 15 same, and flanges extending from opposite edges of said main supporting portion to engage and reinforce the leg sections.

In witness whereof, I hereunto subscribe my name this 28th day of August, A. D., 20 1914.

ENOCH P. STEVENS.
